[57] CLAIM

The ornamental design for a two conductor electrical connector having a locking mechanism, as shown and described.

DESCRIPTION

FIG. 1 is a top right perspective view of a two conductor electrical connector having a locking mechanism showing our new design;

FIG. 2 is a top plan view thereof;

FIG. 3 is a front elevational view thereof;

FIG. 4 is a left side elevational view thereof, the opposite side elevational view being a mirror image thereof;

FIG. 5 is a rear elevational view thereof; and,

FIG. 6 is a bottom plan view thereof.
